UNITED STATES PATENT OFFICE

104,001

DESIGN FOR A DRESS

Albert Ruchman, New York, N. Y.

Application March 6, 1937, Serial No. 68,038

Term of patent 3½ years

To all whom it may concern:

Be it known that I, Albert Ruchman, a citizen of the United States of America, residing in Manhattan, county of New York, and State of New York, have invented a new, original, and ornamental Design for a Dress, of which the following is a specification, reference being had to the accompanying drawing, forming part thereof, wherein,

The design is characterized by the arrangement of the lace inserts in combination with the dress, as shown.

I claim:

The ornamental design for a dress, substantially as shown, and described.

ALBERT RUCHMAN.
